UNITED STATES PATENT OFFICE

2,277,608

WINDOW SEAT

Maurice Rosenblatt, Chicago, Ill.

Application May 2, 1941, Serial No. 391,530

8 Claims. (Cl. 304—24)

This invention has to do with a safety device which together with a window sill forms a seat for a person washing or otherwise servicing the outer side of a window. More particularly the invention relates to a back rest detachably connectible with a window frame and projectible outwardly thereof for the convenience and safety of a person facing inwardly while seated upon the outer sill.

An important object of the present invention is the provision of an improved back rest device adapted to be quickly secured in association with the frame and/or wall about a window opening.

Another object of this invention is the provision of a new back rest device that is adjustable to fit within various sizes of window openings and which, when adjusted to fit openings within a certain size range, is readily interchangeably insertable firmly into assembly therewith without incurring manipulation of auxiliary fastening means such as hooks, screws or bolts.

Another object of the invention is the provision of an improved window seat back rest requiring no special fastening or anchorage devices about the building wall or upon the window frame.

Still another object is the provision of a window seat back rest having a leg portion upon which there are complementary parts unadjustably fixed in spaced relation for clamping about an inner surface section of the wall or frame and an outer edge of the outer window sill to hold the device in place without danger of slippage due to improperly fastened adjustable parts.

A further object is the provision of a new window seat back rest device having clamping bosses upon both its upper and lower sides to enable such device to be transferred without adjustment between adjacent window openings in a double-window frame, by simply inverting the device incident to the change whereby one leg and the boss thereon remains associated with the center column of the frame.

A still further object is the provision, upon a device as the above, of hook means operable to positively retain an extensible leg of the device in either limit of adjustment.

Another object is the provision of a device as the above, consisting of a skeleton-like frame to minimize its weight.

These and other desirable objects inherent in and encompassed by the invention will later appear.

In the drawing:

Fig. 1 is a fragmentary sectional view looking downwardly through a building wall and a win-

dow frame structure incorporated therein, and illustrating in plan view a preferred embodiment of my invention;

Fig. 2 is a vertical fragmentary sectional view taken on the line 2—2 of Fig. 1; and

Fig. 3 is a side elevational view taken on the line 3—3 of Fig. 1.

The present form of the invention is particularly adapted for use in conjunction with a double-window frame structure, and for that reason a window frame of this character is shown in Fig. 1. Since the window frame constitutes no part of this invention, the details of the same are omitted in the drawing, it sufficing to show a building wall 10 in which there is a double-window frame 11 wherein there are window openings 12 and 13 separated by a vertical center column 14. The opening 12 has the usual inner sill 15 and an outer sill 16. Opposed vertical runways 17 are provided for the lower window sash (not shown) and a like pair of runways 18 are provided for the upper window sash (not shown). Corresponding runways for the stiles of lower and upper sashes (not shown) for opening 13 are indicated respectively at 17' and 18'.

Referring now to the device which is adapted to be fitted into either of the openings 12 and 13 as in the manner illustrated with respect to the opening 12, this device will be seen to constitute a generally U-shaped frame 20 consisting of upper and lower U-shaped frame units 21 and 22 which are substantial of identical structure. The upper U-shaped unit 21 includes a leg member 23 which has at its inner or free end a laterally turned flange 24. Said leg 23 also carries an integral upwardly projecting boss member 25, the purpose of which will be explained later. In the outer or closed end of the unit 21 there is a section 26 extending horizontally from the leg 23, and a pair of threaded studs or bolts 27 are carried by the section 26 in apertures provided therefor.

The other leg, 28, of the U-shaped unit 21 is composite in structure in that it is provided with a longitudinally adjustable extension member 29 which has upon its inner end a flange 30 projecting laterally in overlapping relation with the trim about the window frame 11 or inner peripheral portion of the wall 10 as the case may be. The leg 28 carries a pair of bolts 31 which project through longitudinal slots 32 in the slideable member 29 to hold said member in assembly with the leg 28 during longitudinal adjustment, wing nuts 33 being tightenable upon the bolts 31 for holding the member 29 in

a selected longitudinally adjusted position. An upwardly projecting boss 34 is formed integrally with the leg 28, and an extension 35 turned at right angles from the leg member 28 is disposed adjacently to and in horizontal alignment with the extension 26 of the leg member 23, said extension 35 being provided with longitudinal slots 36, of which one is shown in Fig. 2, respectively receiving the shanks of the bolts 27 to permit longitudinal adjustment of said extensions 26 and 35 to take care of different window widths. When such an adjustment has been made of the parts 26 and 35 it may be maintained by tightening wing nuts 37 upon the bolts 27.

Since the lower U-shaped unit 22 is composed of parts respectively corresponding to those thus far described with respect to the upper unit 21, this specification is simplified by designating the corresponding parts by the same respective reference characters with a prime added and thus avoiding a detailed description of these parts. The units 21 and 22 are maintained in assembled spaced-apart relation by four vertical spacer bars 38, 39, 40 and 41, the bar 38 being welded or otherwise securely fastened to the flange-like portions 24 and 24', the spacer bar 39 being secured to and between the flange-like members 30 and 30', and the spacer bars 40 and 41 being connected with and between the units 21 and 22 at their outer or closed ends.

Between the units 21 and 22, at their closed ends, one end of a horizontal bar 42 is connected with the spacer bar 40, and one end of a horizontal bar 43 is connected with the spacer bar 41. These bars 42 and 43 extend in overlapping relation in the same fashion as the extensions 26 and 35. Bolts 44, of which one is shown in Fig. 2, corresponding to the bolts 27 are anchored in the bar 42 and project through slots as 45 in the bar 43. Thus during adjustment in the width of the device, the shanks of the bolts 44 will slide in their slots 45.

In setting up the device for use the wing nuts as 37 upon the bolts 21, 27' and 44 at the outer or closed end of the device will be loosened and the device adjusted in width so that the leg members as 23 and 28 will be spaced apart a distance somewhat less than the inside width of the window opening as 12 with which it is to be assembled. The wing nuts 33 and 33' will be loosened and after the lower sash (not shown) slideable in the runways 17 has been raised the device will be thrust, outer end foremost, outwardly of the opening 12 to press pliable rubber pad members 46 and 47 carried on the spacer bars 39 and 38 against the inner surface of the wall 10. The window trim at the vertical sides of the opening 12 respectively upon the wall 10 and upon the vertical column 14 may for practical purposes be regarded as part of the wall 10. The device will then be lowered to rest the front ends of the legs of the unit 22 upon the inner sill 15 and to slide the boss members 25' and 34' along and against the outer edge of the outer sill 16; see Figs. 2 and 3. This having been done the slideable members 29 and 29' will be slid outwardly with respect to the opening 12 for carrying the pad 46 against the inner side of the wall 10 whereupon the wing nuts 33 and 33' will be tightened. Since the bosses 34' and 25' now bear against the outer edge of the sill 16 while the pads 46 and 47 bear oppositely against the inner side of the wall, the device is clamped in position while resting upon the sill 15. It is, therefore,

expeditely and securely maintained in position so that one may safely sit within the space enclosed by the device upon the sills 15 and 16 while resting his back against the horizontal members as the extension 26 at the outer or closed end of the device.

Inasmuch as the boss 25' and the flange-like members 24' are integrally formed with their leg member as 23' there are no parts which may become unfastened to startle one leaning backwardly against the back rest or to permit him to fall. The adjustable left side of the device, Fig. 1, by virtue of the bolts and nut arrangement as 31—33 enables the pad 46 to be carried against the inner side of the wall at the edge of the opening 12 for lending greater stability to the device, as well as providing an adjustment for different wall thicknesses, but even though accidental sliding should occur between the parts 28 and 29 the opposite leg of the frame which is unadjustable will prevent any considerable amount of slippage.

When the work at one of the openings at 12 has been finished, the device may be quickly transferred to the other opening as 13 and usually without additional adjustment, simply by lifting the device upwardly to free the bosses 25' and 34' from the sill 16 and carrying the device inwardly through the opening 12. The device will then be inserted so the pad 47 will again be associated with the inner face of the column 14 while the pad 46 will be associated with the wall 10 at the opposite side of the frame 11 when the device is projected outwardly through the opening 13 in a manner similarly to that illustrated with respect to the opening 12. At this time the bosses 25 and 34 will be placed against the outer edge of the sill 16 for cooperating with the flanges as 24 and the pads as 47 thereon in clamping the device onto the building wall.

Attention is directed to fastening members 50 and 50' respectively pivoted upon pins 51 and 51' in the slideable members 29 and 29'. These members 50 and 50' have hooks 52 and 53 and 52' and 53'. It will be noted that when the member 29 is slid to its extreme left, Fig. 2, and the wing nut 33 to the left of the member 50 is loosened sufficiently to expose a portion of the shank upon the bolt 31 between this nut and the member 29, the member 50 may be rotated counter-clockwise for hooking the portion 52 over and about the bolt 31 for positively holding the member 29 in this leftmost position. Accidental unhooking of the member 50 from the bolt 31 may be precluded by retightening the nut 33. When the longitudinally slideable member 29 is shifted to its other extreme position to the right, the fastening member 50 will be carried into such association with the right-hand bolt 31 that said member 50 may be pivoted clockwise for placing the hook 53 about said bolt 31 and thus locking the part 29 in its most extended position. The then associated nut 33 may be tightened against the finger 53 for preventing accidental unhooking of the member 50. In this fashion the device may be made absolutely rigid in either extreme of its lengthwise adjustments.

While I have herein shown and described a single embodiment which is thought adequate for clearly disclosing the invention, it should be understood that the invention is not limited to this specific embodiment but comprehends other constructions, arrangements of parts and details falling within the spirit thereof.

I claim:

1. In a window seat device, a generally U-

shaped seatless frame of which the closed end portion is projectible outwardly of a window to effect a back rest, flanges directed laterally outwardly from the free end portions of the frame legs to abut against inner peripheral portions of a wall containing said window, and a boss fixed with respect to a portion of and projecting downwardly from at least one of said legs for engagement with the outer edge of the outer window sill to cooperate with said flanges in clamping the device firmly upon said wall.

2. The combination set forth in claim 1, wherein the boss and flange upon one of said legs and the back portion of the frame are fixed longitudinally of said leg to insure the back portion against accidental displacement outwardly from the window while in use and to insure secure cooperative clamping action of the boss and flange against opposite sides of the wall, and wherein the other of said legs comprises a longitudinally adjustable part upon which the flange pertaining to such leg is mounted, whereby the distance between the flange and boss on said leg can be changed to accommodate different wall widths.

3. In a window seat device, a generally U-shaped frame of which the closed end portion is projectible outwardly of a window to effect a back rest, flanges directed laterally outwardly at the free ends of the frame legs to abut against inner peripheral portions of a wall containing said window, and bosses projecting respectively upwardly and downwardly from at least one of the frame legs for engagement with an outer portion of the outer sill of said window to cooperate with said flanges in mounting the device upon said wall, said bosses adapting the device to be invertible and being alternatively engageable with the sill depending upon which side of the device is turned upwardly.

4. In a window seat device, a generally U-shaped frame of which the closed end portion is projectible outwardly of a window to effect a back rest, flanges directed laterally outwardly at the free ends of the frame legs to abut against inner peripheral portions of a wall containing said window, and bosses projecting respectively upwardly and downwardly from each of the frame legs for engagement with the outer edge of the outer sill of the window to cooperate with said flanges in clamping the device upon the wall, said bosses adapting the device to be invertible and the upwardly and downwardly projecting flanges being alternatively engageable with said sill depending upon whether the device is inverted.

5. In a window seat device, a frame comprising a leg member for disposal perpendicularly to and within the opening of a window adjacently to a vertical side thereof, a member directed laterally from an outer portion of said leg to effect a back rest, abutment means upon said member

for abutting against an outer edge portion of the outer sill for said window, a member adjustable longitudinally upon said leg member, means upon said longitudinally adjustable member for engaging an inner surface portion of the wall containing the window to cooperate with said abutment means in clamping the device upon said wall, a plurality of studs spaced longitudinally of and upon one of said leg or longitudinally adjustable members, slot means extending longitudinally in the other of such members and receiving said studs to cooperate therewith for holding such members in assembly during their relative adjustment, and hook means upon said other member at a point between said studs and respectively hookable thereabout for positively retaining the longitudinally adjustable member in either limit of its adjustment.

6. In a window seat device, a generally U-shaped frame comprising a pair of horizontal vertically aligned and spaced strap-like U-shaped members of which the closed end portions are projectible outwardly of a window to effect a back rest, flange-like portions directed laterally outwardly respectively from the free ends of the legs of said members whereby such portions upon corresponding legs of the members are vertically aligned, spacer members interconnecting the vertically aligned of said flange-like portions, pads upon said spacer members for engaging the inner face of the wall containing the window, spacer members inter-connecting portions of said U-shaped members adjacently to their closed ends, bosses projecting downwardly from the legs upon the lower of said members for abutment with the outer edge of the outer sill for said window to cooperate with said pads in preventing movement of the device normally to the window.

7. The combination set forth in claim 6 and wherein there are also bosses projecting upwardly from the upper of the U-shaped members for engaging the outer side of said sill and thus cooperating with the pads as aforesaid when the device is inverted.

8. In a window seat device, a generally U-shaped seatless frame of which the closed end portion is projectible outwardly of a window to effect a back rest, flanges directed laterally outwardly from the free end portions of the frame legs to abut against inner peripheral portions of a wall containing said window, said legs constituting flat metal members arranged in respective planes substantially normal to the plane of the U-shaped frame, and a boss projecting downwardly from at least one of said legs substantially within a common plane therewith, for engagement with the outer sill of said window to support the closed end portion of the frame while said outwardly turned flanges abut the inner peripheral wall portions as aforesaid.

MOURICE ROSENBLATT.
